C. H. KAMM

MOUNTING STRUCTURE

Filed Oct. 20, 1923

UNITED STATES PATENT OFFICE.

CARL H. KAMM, OF TWO RIVERS, WISCONSIN, ASSIGNOR TO HAMILTON MANUFACTURING COMPANY, OF TWO RIVERS, WISCONSIN, A CORPORATION OF WISCONSIN.

MOUNTING STRUCTURE.

Application filed October 20, 1923. Serial No. 669,857.

To all whom it may concern:

Be it known that I, CARL H. KAMM, a citizen of the United States, residing at Two Rivers, in the county of Manitowoc and 5 State of Wisconsin, have invented a certain new and useful Improvement in Mounting Structures, of which the following is a full, clear, concise, and exact description.

My invention relates to mounting structures and is of particular utility when employed for positioning or carrying a slide rule. The mounting may be of such a nature that the rule may be maintained in a position to be always properly observable 10 whether in use or at rest, the mounting also enabling the rule to be adjusted by one hand.

In the preferred embodiment of the invention the mounting structure includes an elongated block having an angular recess 20 formed in and extending along one long side thereof, and a second angular recess formed in and extending along an adjacent long side of this block, the bases of these recesses being in angular relation and having a common dividing edge extending along the block, and a second elongated block in hinged connection with the first and received in the first recess of the first block and itself having an angular recess formed in and extending along one of its long sides.

The means by which the two blocks are placed in hinged connection desirably resides in a coiled spring structure anchored to the two blocks and extending across the 35 base of the first recess in the first block.

The invention will be more fully explained by reference to the accompanying drawing in which Fig. 1 is a perspective view illustrating the preferred form of 40 mounting and a slide rule carried thereby; Fig. 2 is a perspective view illustrating the two blocks spread apart to enable the slide rule to be readily received, the slide rule not being shown in this figure; Fig. 3 is a 45 sectional view on line 3—3 of Fig. 1; Fig. 4 is a bottom view, on a smaller scale; and Fig. 5 is a sectional view on line 5—5 of Fig. 3.

Like parts are indicated by similar characters of reference throughout the different 50 figures.

The mounting structure includes an elongated base block 1, having an angular recess 2 formed in and extending along the top 55 long side thereof. The second angular

recess 3 is formed in and extends along an adjacent long side of this block, this side of the block being inclined rearwardly. The bases 4 and 5 of the recesses 2 and 3 are in angular relation, the recess base 5 being inclined similarly to the inclined side of the block. The two recess bases have a common dividing edge 6 extending along the block. A second elongated block 7 is received in the first recess 2 of the block 1 and itself 60 has an angular recess 8 formed in and extending along one of its long sides. The base 9 of the recess 8 is normally substantially in the plane of the base 5 of the second angular recess 3 in the first block, whereby 65 the angular recess 8 in the second block constitutes a widening continuation of the second angular recess 3 in the first block.

The wall of one of the two recesses 3, 8, (preferably the recess 8) that is angular 70 to the base of this recess overhangs this recess base.

The means by which the two blocks are assembled in hinged relation desirably includes two coiled springs 10 and 11 each anchored 75 to the two blocks and extending across the base 4 of the first recess 2 in the first block 1. The springs are partly received in the holes 12 in the block 1, and partly in the holes 13 in the block 7, the hole receiving 80 each spring being aligned when the second block is held against the first by the springs. The lower end of each spring is anchored to the block 1 by means of an anchor pin 14 held in the slot 15 formed in the bottom of 85 the block 1 and crossing the corresponding hole 12. The other end of the said spring is anchored to the block 7 by means of a pin or nail 16 driven into the block 7 and passing through the hole 13. The springs serve 90 to permit the second block to be shifted upon the first, as illustrated in Fig. 2, to temporarily widen the space jointly formed by the recesses 3 and 8 readily to permit an object to be inserted into this space, where- 95 after the blocks may be restored to their normal relation to hold the object in place.

The object illustrated upon the mounting structure is a slide rule whose base member 17 is confined between the recess sides 100 18 and 19, the latter recess side overhanging the adjacent recess base 9 and sloping to receive the upper sloping side 20 of the base member of the slide rule.

Friction pads, preferably in the form of 110

rings of rubber 21, are received in the bottom of the block 1 and project downwardly therefrom a slight distance whereby the mounting structure may not readily slip upon the drawing board or other support. The base member of the slide rule is so firmly held that the adjustable member 22 thereof may readily be moved with respect to the base member without shifting this base member, it being not necessary to hold this base member nor the mounting for the rule when adjusting the rule, owing to the weight of this mounting and the frictional engagement thereof with the support for the mounting that is afforded by the friction pads. A little practice will readily enable the user further to hold the mounting in place by one or more fingers while the thumb and another finger or fingers are employed in shifting the adjustable member 22 of the slide rule or the transparent sliding member 23 of the rule.

It is obvious that changes may be made without departing from the spirit of my invention.

Having thus described my invention I claim as new and desire to secure by Letters Patent the following:—

A mounting structure including an elongated block having an angular recess 30

formed in and extending along one long side thereof, a second angular recess formed in and extending along an adjacent long side of this block, the bases of these recesses being in angular relation and having a common dividing edge extending along the block; a second elongated block received in the first recess of the first block and itself having an angular recess formed in and extending along one of its long sides 35 and whose base is substantially in the plane of the base of the second angular recess in the first block whereby the angular recess in the second block constitutes a widening continuation of the second angular recess 40 in the first block, the wall of the recess in the second block that is angular to the base of this recess overhanging this recess base; the base of the second recess of the first block and the base of the recess in the second block sloping backwardly and a coiled 45 spring structure anchored to the two blocks and extending across the base of the first recess in the first block.

In witness whereof, I hereunto subscribe my name this 8th day of October A. D., 1923.

CARL H. KAMM.
